Fig. 3

FIG. 1 is a front perspective view of a tractor drawn forage harvester embodying our new design;

FIG. 2 is a perspective view of the side shown in FIG. 1;

FIG. 3 is a rear perspective view thereof; and

FIG. 4 is a perspective view of the side opposite that shown in FIGS. 1 and 2.

The dominant features of our design reside in the portions shown in full lines.

We claim:

The ornamental design for a tractor drawn forage harvester as shown and described.
